UNITED STATES PATENT OFFICE.

LEO F. FAY, OF ECORSE, MICHIGAN.

WASHING-MACHINE.

1,390,520.

Specification of Letters Patent. Patented Sept. 13, 1921.

Application filed February 9, 1920. Serial No. 357,215.

To all whom it may concern:

Be it known that I, LEO F. FAY, citizen of the United States, residing at Ecorse, county of Wayne, State of Michigan, have invented 5 a certain new and useful Improvement in Washing-Machines, and declare the following to be a full, clear, and exact description of the same, such as will enable others skilled in the art to which it pertains to 10 make and use the same, reference being had to the accompanying drawings, which form a part of this specification.

In the operation of washing machines of 15 the type wherein the clothes are agitated by a reciprocating member it is desirable that the parts be so disposed as to insure proper circulation of the washing fluid through the clothes while the latter are constantly agitated and subjected to impacts so delivered 20 by the mechanism that they do not tend to become bunched or matted together. It is also desirable that the mechanism be so arranged to operate smoothly and easily while at the same time it is shielded from contact 25 with the washing fluid.

This invention relates to a washing machine of a type wherein the clothes are placed in a stationary retainer and are agitated by yieldingly operating a movable 30 member or beater which not only strikes or paddles the clothes but also forces water and air through them in such a way as to effectively cleanse them, the parts being so disposed that the washing liquid does not get 35 upon the driving mechanism of the machine while at the same time, simplicity of construction is combined with efficiency of operation.

The invention consists in the matters hereinafter set forth, and more particularly 40 pointed out in the appended claims.

In the drawings:

Figure 1 is a view in elevation of a machine that embodies features of the invention.

Fig. 2 is a view in vertical longitudinal section through the clothes container or tub, with parts shown in elevation.

Fig. 3 is a view in horizontal section of 50 the device taken on or about line 3—3 of Fig. 2.

Fig. 4 is a view in detail, partially in section and partially in elevation, of a driving mechanism for the agitator or beater.

Fig. 5 is a view in section taken at right angles to the plane of Fig. 4, showing the driving mechanism in detail.

Fig. 6 is a view in detail, partially in section and partially in elevation, of one form of wringer driving mechanism. 60

Fig. 7 is a detail sectional view taken on or about line 7—7 of Fig. 6 showing means for securing the wringer in any desired angular relation to the rest of the mechanism.

Fig. 8 is another view in detail of the 65 adjustable wringer connection.

Fig. 9 is a view in detail of a reverse clutch driving mechanism for a wringer, taken on or about line 9—9 of Fig. 6.

Fig. 10 is a detail sectional view through 70 the safety clutch taken on or about line 10—10 of Fig. 2.

Fig. 11 is a view in detail, taken on or about line 11—11 of Fig. 2 of the means for adjustably securing the beater to the beater 75 spindle.

As herein shown in preferred form, a clothes container A which is preferably cylindrical, is suitably mounted on a frame or supporting members a that are designed 80 to combine strength with lightness and are carried by casters a¹. A removable cover a² closes the container and a drain cock a³ is likewise provided.

An annular beater or agitator B with a 85 convex outer wall b and cylindrical inner wall b¹ has a central head or convex dome b² apertured as at b³ to provide for the efflux of water and bored to be adjustably secured on an upright beater spindle b⁴. As one preferred form of adjustable connection, a cross pin b⁵ passes through the hub b⁶ of the crown b² and through any one of a series of apertures b⁷ in the spindle b⁴, being held in desired position by a spring finger b⁸ swing- 95 ing on a pivot b⁹ of a lug b¹⁰ formed on the hub. Preferably, the beater is integrally formed although it may be otherwise made.

The annular cavity formed by the walls b and b¹ partially traps air as well as liquid 100 and as the air is compressed on the downward stroke it ejects the water through the clothes which it encounters with considerable force, while the shape of the inner well formed by the wall b¹ and the crown b² insures ease of action of the beater and causes water to be forced outwardly through the openings b³ and downwardly along the face of the wall b so as to insure good circulation throughout the body of liquid of the 105 tub.

If desired a plurality of relatively small apertures may be provided in the wall b¹, for the escape of air, to relieve the pressure

within the annular cavity though it is not essential.

The spindle is reciprocable through an elongated sleeve a^4 properly mounted in the tub, or container A and provided with a stuffing box or gland a^5 to prevent leakage.

A hollow sleeve b^{11} is pivoted as at b^{12} to the lower end of the spindle b^4 of which it forms a continuation. A motor C is suitably supported as by members a^6 secured to the supports a with its main shaft c connected through a universal joint c^1 and a safety clutch c^2 with a worm drive shaft d mounted in a worm casing D suitably held by supports d^1 on the main frame below the tub.

The universal joint is of conventional type and the safety clutch may be of any suitable form but as herein indicated, consists of a disk rotated by the universal joint c^1 , and provided with radially disposed springs c^3 that are adjustably compressed by screws c^4 so as to engage on driving balls c^5 socketed in depressions in the worm shaft d whereby the latter is normally driven but is released when undue resistance, which otherwise might wreck the mechanism, is encountered.

A worm d^2 on the shaft d , in turn rotates a transverse shaft d^3 which is longitudinally reciprocable as well as rotatable in the casing D. Reciprocation is accomplished by a shifting lever d^4 operating a fork d^5 that embraces a shift collar d^6 on the shaft d whereby a tenoned end portion d^7 of the shaft may be moved in or out of the frictional engagement with the slotted end of a sleeve hub on which the driving wheel E is keyed. This wheel is preferably of sufficient weight to act as a fly wheel for the mechanism.

A pitman rod e^1 couples the fly wheel E and a lever e^2 that oscillates on a pin e^3 , while its otherwise free end is connected to a piston rod e^4 . The latter is reciprocable in the beater spindle extension b^{11} and carries a piston head e^5 which is yieldingly held between the fixed head of the sleeve b^{11} and a removable head b^{13} by opposing springs b^{14} and b^{15} . A forked member b^{16} , either integral or bolted to the spindle extension b^{11} may be provided to straddle the lever e^2 , to prevent any tendency of the spindle extensions from rotating upon its own axis.

A burner I is provided for heating the water in the tub.

In operation, the motor oscillates the spindle b^4 through the medium of the safety clutch and the clutch by which the driving wheel is thrown into gear, and effects the necessary reciprocation of the beater B to produce the desired result.

The worm shaft d is likewise connected suitably by any preferred form of driving

mechanism to the main roll shaft of a wringer F. While the mechanism herein shown is perhaps the best fitted for the purpose, it is not described in detail as it does not *per se* form a part of the invention. The wringer itself, which is thus operated by the same motor as the washing beater, is mounted on an upright tubular support G of the machine by a fitting H and may be locked in desired angular position by means of a spring-pressed keeper or latch bolt g^1 in the hub h of the fitting which snaps into any one of a series of apertures in the support g .

As a result of this construction a washing machine is obtained which effectively cleanses the clothes placed therein without danger to them, as the yielding stroke given the baffle or beater prevents this. The peculiar annular shape of the beater does not permit the clothes to become matted or knotted together at any one point and at the same time it causes an even circulation of the water at all points, the air which is trapped in the upper portions of the annular chamber acting to eject the water forcibly through the garments and thereby to aid in the cleansing operation.

The arrangement of the bearing of the spindle with a length to minimize leakage together with the housing of the mechanism below the tub, avoids any deleterious effect to the mechanism from contact with the washing liquid of the tub and thereby increases the efficiency of the device.

Obviously, changes in the details of construction may be had without departing from the spirit of my invention and I do not care to limit myself to any particular form of arrangements of parts.

What I claim is:

1. A washing machine comprising a clothes container, a beater in the container, a spindle extending through the bottom of the container and connected with the beater, a motor located below the container and a yieldable device connected with the motor and with the spindle and located wholly below the container, said yieldable device comprising a cylinder, a piston rod having a head operating within the cylinder and springs located within the cylinder and yieldably engaging the piston head above and below the same.

2. A washing machine comprising a clothes container, a beater having an outer annular cavity, an inner water circulating well extending from the top to the bottom of the beater and provided above the annular cap with radial outlets and having inlets located below the outlets and communicating with the said annular cavity, a longitudinally reciprocable member on which the beater is secured extending through the base of the receptacle, a motor secured below the receptacle and mechanism connecting the

motor and member for reciprocating the latter.

3. In a washing machine, a clothes beater provided with an outer, annular downwardly open air and water cavity and an inner circulating well extending above the said cavity and covered by a deflecting dome provided with lateral efflux openings, said well forming an open chamber from the dome to the bottom of the beater.

4. In a washing machine, a beater having an outer annular downwardly open air and water retaining chamber and an inner circular well extending from the bottom of the beater to a point above the cavity and provided with a convex dome having lateral efflux openings, said well forming a chamber from the bottom of the beater to the dome, an upright reciprocating spindle extending through the dome and means for locking the dome and upright member in desired, adjusted relation.

5. In a washing machine, a beater comprising an inner cylindrical shell provided at a point between its top and bottom with inlet perforations and having a dome-shaped top, said shell being also provided at the base of the dome with radial outlet openings and an annular flange or wall extending downwardly and outwardly from the shell at a point above the said perforations and forming an outer annular air and water chamber.

6. In a washing machine, a clothes container, a beater comprising an inner cylindrical shell open at the bottom and provided at the top with a thickened dome having a central upwardly extending sleeve, said shell being provided at the base of the dome with radial outlets and having inlet perforations spaced from the said outlets and a

downwardly and outwardly extending flange or wall united with the shell above the said perforations and forming an outer annular air and water cavity and a spindle extending through the well and secured in the sleeve of the said dome.

7. A washing machine comprising a clothes container, a circular clothes beater in the container, a spindle longitudinally reciprocable through guide means in the base of the receptacle adjustably secured to the clothes beater, a motor mounted below the receptacle, a sleeve located wholly below the container and pivoted to the lower end of the spindle below the tub, a piston reciprocable in the sleeve, springs in compression each between the piston and a head of the sleeve and operating connections between the motor and piston for reciprocating the latter.

8. A washing machine comprising a clothes container, a clothes beater within the container, a spindle extending through the bottom of the container and connected with the beater, a sleeve pivoted to the lower end of the spindle and located below and arranged exteriorly of the container, a piston reciprocating in the sleeve, springs each in compression within the sleeve and operating above and below the piston, a lever pivoted to the machine and connected to the piston, a pitman wheel operatively connected to the lever, a motor and driving connections between the motor and the pitman wheel.

In testimony whereof, I sign this specification in the presence of two witnesses.

LEO F. FAY.
